I. W. WEPPLO

COLLAPSIBLE TUBE CLOSING MACHINE

Filed Oct. 28, 1921

INVENTOR:

ISAAC W. WEPPLO

Oliver J. Martin

HIS ATTORNEY.

UNITED STATES PATENT OFFICE.

ISAAC W. WEPPLO, OF CHICAGO, ILLINOIS.

COLLAPSIBLE TUBE-CLOSING MACHINE.

Application filed October 28, 1921. Serial No. 511,201.

To all whom it may concern:

Be it known that I, ISAAC W. WEPPLO, a citizen of the United States, residing at Chicago, in the county of Cook and State 5 of Illinois, have invented new and useful Improvements in Collapsible Tube-Closing Machines, of which the following is a specification.

The present invention is directed to collapsible tubes, and refers particularly to means for supporting such tubes during the operation of folding the end of the tubes.

Machinery for closing collapsible tubes by folding the large bottom end of the tubes 15 are well known and widely distributed. The object of the present invention is to provide improved means for supporting such tubes while they pass through the folding machine in order that the folds may present 20 a pleasing appearance and so that they may be tight and substantial.

To this end the invention resides in the combinations hereinafter fully set forth and illustrated in the accompanying drawing, 25 of which:

Fig. 1 shows, in side elevation, a tube closing machine embodying the invention.

Fig. 2 is fragmentary view of one of the tube supports, and illustrating the method 30 of attaching this part to machine of Fig. 1.

Fig. 3 is a plan view of the support and drawn substantially in agreement with the preceding views.

The tube closing machine, in which I have 35 shown my invention embodied, is of a well known, largely used type, and for this reason a very short description of this machine is deemed sufficient. The machine comprises a stationary frame A, on which a turn-table 40 B is mounted to revolve, and the latter is fitted to receive collapsible tubes C, and to carry these tubes past suitable folding devices D. The turn-table and the folding devices are interconnected for properly timed 45 motion, through the medium of suitable gearing E, and the machine is connected to be driven by a prime mover, as by a belt pulley F. The folding devices are operated from a cam shaft 1, which is connected for 50 continuous rotation by the said gearing. The

turn-table, on the other hand, is given a step by step movement for the purpose of carrying each succeeding tube C into registration with the folding device D, through the medium of suitable gear wheels 2 and 3. 55 And it is important to note, in order fully to understand the following description, that the turn-table advances one step every time the cam shaft 1 makes two complete revolutions. It is also to be noticed that there 60 is a plurality of sockets 4 capable of holding tubes, and that each step movement of the turn-table brings a new tube into alinement with the folding devices D. The gear wheel 2 is divided into a plurality of equal zones, 65 each comprising a toothed portion 2^a, and a blank portion 2^b from which the teeth have been removed. In the course of its continuous rotation, each toothed portion of the wheel comes into engagement with the gear wheel 3, imparting to the latter the intermittent rotating movement, which 70 serves to bring the tubes C into alinement with the folding elements D. The mechanical combination formed by the gears 2 and 75 3 is usually termed a geneva movement. To make such movement more reliable it is customary to mount co-operating discs on the sides of the gears, to prevent overthrow, as well known to those versed in the art. But 80 as the specific intermittent gear construction forms no part of this invention, such discs have not been illustrated in the drawing.

The socket 4 takes the form of a vertically disposed cylindrical member perforated to 85 receive a tube C and rigidly secured on a bracket 5, which latter is hung on the turn-table. The tubes are in the first instance, filled with the material for which the tubes have been provided. Such tubes are made 90 of thin flexible metal, and it is found very difficult to retain their shape unchanged during the filling operation and in placing the tubes in the closing machine, because a slight pressure of the operator's fingers is 95 sufficient to flatten the tubes. For this reason it is necessary to provide enough room within the sockets 4 to make certain that the tubes will drop into place without sticking. Because, should a tube stick, and 100

not quite bottom in the socket, it will be found that the folding devices cannot function properly and that the tube will be ruined.

- 6 On the other hand, it is necessary to hold the tubes in a certain position within the sockets. It has been found that any irregularity in the positioning of the tubes will affect the tube closing operation. If the 10 tube has much freedom within the socket, and can tip over to one side, it may lean to that side sufficiently to drop out of registration with the folding devices, and the tube may be ruined, or at last incompletely 15 closed. Or if a tube is flattened at one place, by the operator's fingers, it may seek an inclined position, with the same result. The socket 4 is made with a perforation 4^a large enough in diameter to admit a tube 20 even although the shape of such tube is considerably affected, in handling. And means are provided on each socket capable of urging all the tubes on the turn-table into the proper position for alinement with the folding devices. Such means may take 25 the form of a resilient member 6, which has a finger portion 6^a extending into the socket for engagement with the side of the tube. This resilient finger exerts a backward pressure 30 on the tube, relative to the direction of movement of the turn-table, which pressure serves to hold the tube in a vertical position against the opposite side of the wall in the socket. The resilient finger might be 35 constructed to urge the tube forward, but if the tube in that case should collide lightly with the folding device, such collision would operate to tip the tube backward out of alinement with the folding elements. The 40 resilient finger must not under any circumstances urge the tube sidewise, because in that case the folding members would not function properly.

Attention is directed to the construction 45 of this resilient member 6 and to the manner in which the socket is shaped to receive said member. An annular groove 4^b is cut in the outer surface of this socket, and this groove communicates with a vertically disposed slot 4^c, rising therefrom. The member 6 comprises an annular loop slightly 50 smaller in diameter than the bottom of the groove 4^b, and the aforesaid finger 6^a, which extends upward from the loop and projects 55 through the slot 4^c for the purpose hereinbefore stated. It is readily seen that this resilient member may be attached simply 60 by slipping the loop over the top of the socket, whereupon it instantly springs into place. In order to remove this member it is only required to spring it open sufficiently 65 to slip it over the top of the socket. This feature is important because it is necessary to remove the member frequently in order 70 to clean the parts. Tubes of this character

are widely used for dental cream, paint, glue, and other sticky substances. Much care is not exercised in filling the tubes, and when the tubes are passed through the folding machine they are usually more or less covered with the material they contain. This material settles within and around the socket, making it difficult to remove the resilient member, unless the latter, as herein explained, is capable of removal merely by 75 pushing the finger 6^a out of the slot 4^c and then pulling upward said finger, causing the loop 6 to leave the groove 4^b and to slide over the socket. Fastening the resilient member by means of screws or other devices 80 requiring the employment of special tools for their removal, has not been found practical, because such parts will always be found covered by a more or less hardened or dried layer of the overflowing material of 85 the tube contents.

It is well at this time to point out, and it should be noted, that the socket perforation is made with a shoulder portion 4^d, upon which the shoulder 7 of the tube C is 90 caused to rest, and that the portion 4^e, of the perforation, below the shoulder 4^d, is of a size freely to accommodate the screw-cap 8 of the tube. In other words, I am resting 95 the tube on the shoulder 7, whereas it is common practice to rest the screw-cap of the tube on the bottom of the socket. But, if the socket is made with a bottom, it is observed that it soon becomes filled with 100 overflow material obstructing the space for the tube, and that such material is difficult to remove when partly dry and hard. The socket of my invention is open clear through, and the overflowing material can escape 105 through the bottom and drop to the floor to a drip pan below. The socket of my invention is therefore substantially self cleaning.

It is customary to repeat the folding operation. The first operation presses the end 110 of the tube flat and folds it over once. The tube is then elevated as much as it has been shortened by the first folding operation, whereupon the repeated pressing operation tightens the first fold, and a second folding 115 operation completes the sealing of the tube. In order to permit of such elevation, the bracket 5 of the tube socket has been made with a vertically disposed post 9, which is slidably fitted in a perforation of the turn-table. Normally the bracket rests, by its own weight, on the turn-table, and a spring 10 is placed between the bottom surface of the latter and the lug 5^a of the bracket for 120 the further purpose of urging the parts into such normal position, should overflow material penetrate into the bearing of the post 9 and influence the freedom of sliding movement of the parts.

It was hereinbefore mentioned that the 130

cam-shaft 1 makes two complete revolutions every time the turn-table advances one step. During the first rotation of the cam-shaft, the first fold is completed. Attention is now directed to a gear wheel 11, which forms part of the aforesigned power and time gearing E. This gear wheel is, on its face, provided with a cam-groove 11^a, in which rides a pin or roller 12 of an arm 13, and the latter is rigid on a rock-shaft 14, seated in the machine frame. To this inner end of this rod is fastened a lifting arm 15, which extends forward into the path of the bottom of the socket bracket 5. The cam-groove 11^a is made in two semi-circular portions, one having a longer radius than the other. While the pin 12 rides in the smaller groove portion it is tilted forward and the lifting arm 15 is then down, out of the path of the bracket 5. 20 But the moment the pin passes into the larger groove, the arm must necessarily follow the movement of the pin, with the result that the lifting arm is raised, and that it engages the bottom of the bracket and elevates the bracket, together with the socket 4 and the therein supported tube, to the proper position required for making the second fold.

The spring 10 serves a double purpose. In 30 the first place it urges the bracket 5 downward, as already explained, and its further purpose is to maintain the bracket firmly in position radially, in order that it may not vibrate back and forth on the post 9. It may 35 be said that the bracket can be so nicely fitted to slide on the edge of the turn-table that no lost motion and consequent vibration can occur. But when it is remembered that all the brackets are frequently detached, in order 40 to remove the overflow of material, and that they are not likely to be put back in the same order, it is not such a simple matter to obtain a perfect fit between the brackets and the turn-table. Furthermore, such a perfect 45 fit is objectionable because the overflowing contents of the tubes will reach into and settle on the abutting sliding surfaces and, on account of their stickiness, retard or even prevent the movement of the close fitting brackets on the table. In view of the foregoing 50 it is to be noted that the bracket and its post are purposely loosely fitted by allowing a considerable amount of play between the parts, and that the spring 10 is wound round the post in the direction opposite to the travel of the turn-table, whereby the bracket constantly is urged rearward, relative to the direction of travel, and firmly held pressed against the periphery of the 55 table. The bracket is not pressed forward, because if it happened to touch the folding devices during its forward movement, it would be forced rearward, against the tension of its spring, and out of alinement with the folding elements.

I claim:

1. In a collapsible tube folding machine, the combination with a turn-table and tube folding devices, of means on said table for supporting tubes to be closed, said means including elements for yieldingly maintaining the tubes in alinement with said folding devices. 70
2. In a collapsible tube closing machine, the combination with a turn-table and folding devices, of means attachable to said table for supporting tubes to be closed and vertically slidable, and resilient means urging said supporting means downward and rearward. 75
3. In a collapsible tube closing machine, the combination with a turn-table and folding devices, of a plurality of brackets vertically slidable on said table, means yieldingly maintaining said brackets depressed and rearwardly pressed, and a tubular cylinder on each of said brackets, said cylinder having an inside shoulder intermediate its ends for supporting a tube to be closed. 80
4. In a collapsible tube closing machine, the combination with a turn-table and folding devices, of means attachable to said table and capable of supporting a tube to be closed, said means including a cylindrical member having a cylindrical bore therethrough of a size freely to accommodate a tube to be closed, there being in said bore a shoulder supporting said tube, and yielding means capable of maintaining said tube in the proper position for registration with the said folding devices. 90
5. In a collapsible tube closing machine, the combination with a turn-table and folding devices, of a plurality of brackets attachable to said table, and tube sockets vertically fixed in said brackets, each socket having a shouldered perforation of a size freely to support a tube, and yielding means attachable to the socket and urging the tube into proper position of alinement with the said folding devices. 105
6. In a collapsible tube closing machine, the combination with a turn-table and folding devices, of tube sockets attachable to said table, each socket perforated to receive a tube and made with an external annular groove, from which rises a vertically disposed slot through the wall of the socket, and resilient means seatable in said groove, said means having a finger extending through the said slot and yieldingly maintaining the tube in a position of proper registration with said folding devices. 115
7. In a collapsible tube closing machine, the combination with a turn-table and folding devices, of a series of brackets having vertical posts slidable in perforations of said table, means yieldingly maintaining said brackets downwardly and rearwardly pressed, a tubular socket in each bracket for 120
- 130

supporting a tube to be closed, and resilient means attachable to said socket for the purpose of maintaining said tube rearwardly pressed in the socket.

5 8. In a collapsible tube closing machine, the combination with a turntable and tube folding devices, of a series of vertically mov-

able tube supports on said table, and yielding means on said supports for maintaining the supported tubes in alinement with the ¹⁰ folding devices.

In testimony whereof I have hereunto affixed my signature.

ISAA� W. WEPPLO.
